UNITED STATES PATENT OFFICE.

JOHN F. WING, OF MAYWOOD, ILLINOIS.

SHEET-METAL-WORKING MACHINE.

1,031,605.

Specification of Letters Patent.

Patented July 2, 1912.

Application filed November 5, 1909. Serial No. 526,456.

To all whom it may concern:

Be it known that I, JOHN F. WING, a citizen of the United States, and resident of Maywood, county of Cook, and State of Illinois, have invented certain new and useful Improvements in Sheet-Metal-Working Machines, of which the following is a specification, and which are illustrated in the accompanying drawings, forming a part 10 thereof.

The invention relates to machines for working sheet metal, and particularly to those comprising punches and dies adapted to automatically cut and fold articles from 15 blank sheets of tin-plate and similar materials.

The object of the invention is to simplify and improve the construction of machines of this class; and the invention is exemplified in the mechanism hereinafter described and illustrated in the accompanying drawings, in which—

Figure 1 shows in side elevation a sheet metal working machine embodying the invention; Figs. 2 and 3 are plan views of the same, Fig. 2 showing the forward end of the machine, and Fig. 3 its rear end; Fig. 4 is an end elevation of the same; Fig. 5 is a longitudinal sectional view taken on the line 5—5 of Fig. 2; Fig. 6 is a longitudinal vertical sectional view taken on the line 6—6 of Fig. 3; Fig. 7 is a longitudinal vertical sectional view taken on the line 7—7 of Fig. 3; Figs. 8, 9 and 10 are detail sectional views, the planes of the sections being indicated by the lines 8—8, 9—9 and 10—10, respectively, on Figs. 1 and 3; Fig. 11 is similar to Fig. 10 but illustrates the parts in a different position of movement; Fig. 12 is a detail sectional view taken on the line 12—12 of Figs. 1 and 3; Fig. 13 is a detail sectional view taken on the line 13—13 of Figs. 1, 2 and 5; Fig. 14 is a sectional view taken on the line 14—14 of Figs. 1 and 2; Fig. 15 shows the central portion of the machine in perspective; Fig. 16 is a detail sectional view illustrating a form of feed mechanism employed upon the machine; Figs. 17, 18 and 19 illustrate a form of clutch employed upon the machine, Fig. 18 being a sectional view taken on the line 18—18 of Fig. 17; Fig. 20 shows in perspective an

electrical switch employed upon the machine; Figs. 21 to 29, inclusive, illustrate the article produced by the machine in its several stages of development; Fig. 30 shows the stock from which the articles are produced; Fig. 31 is a detail sectional view taken on the line 31—31 of Fig. 3; Fig. 32 is a perspective view of a form of frame 60 which may be employed for receiving articles produced in the machine; Figs. 33 and 34 are perspective views of certain dies shown in Fig. 6; and Figs. 35 and 36 are perspective views of certain dies shown in Fig. 7.

The machine illustrated is of a form adapted to produce tin car seals like that shown in Fig. 29 of the drawings, from blank sheets of tin-plate of rectangular 70 shape. In the operation of the machine, a plurality of blanks, such, for example, as that shown at *a* in Fig. 21, and comprising a head 50 and a strap 51, are punched from a sheet of tin *X*, Fig. 30. These sheets of 75 tin stock *X* are preferably of greater width than the length of the blank *a*, the stock being operated upon progressively from end to end, thus leaving a multilated sheet comprising a plurality of straps 52, connected 80 at one end by a continuous band 53, which, upon being reversed, may be delivered to the machine a second time and a second series of blanks *a* punched therefrom, the straps 52 serving to form the straps 51 of the 85 blanks and the heads 50 of the blanks being punched from the continuous band 53.

The machine comprises a plurality of dies which operate upon the blank *a* in succession, and feed mechanisms for advancing 90 the stock from which the blanks are punched and for advancing the blanks upon the several dies and delivering them in the form of completed car seals at the end of the machine. The punch for cutting the blanks 95 from the stock is generally designated in the drawings by the letter *A*. The several dies are generally designated by the letters *B*, *C*, *D*, *E*, *F*, *G*, *H* and *I* respectively. In Figs. 21 to 29 inclusive of the drawings, the 100 result of the operation of the punch *A* and the several dies is illustrated, the blank cut by punch *A* being generally designated by the letter *a* as before described, and the form

which this blank takes after its manipulation by each of the several dies B, C, D, E, F, G, H, and I, being shown at b, c, d, e, f, g, h and i respectively. Apparatus for 5 numbering the finished seals is shown in outline at J.

The machine preferably comprises a table, generally designated by the numeral 54. This table is supported in a horizontal 10 position by standards 55, 56 and 57, the standards, designated by the numerals 55 and 56, being connected at the top by a bed plate 98 which extends beneath the table 54 adjacent one of its ends and serves for 15 supporting the punch A. The punch A is carried by a pair of uprights 62, 63, which rise from the bed plate 98 at each side of the table 54, and are connected at the top by a cross piece 97. The punch comprises a 20 vertically movable punch head 58 and a coöperating stationary die-block 59, Figs. 4 and 5. The punch head 58 has a vertical sliding movement between ways 60 and 61 provided upon the inner faces of the standards 62, 63, these ways being of the form 25 usually employed for the punch heads of metal punching machines. A drive shaft 64 is journaled in the standards 62, 63, above the punch head 58, and an eccentric 65, 30 formed upon the drive shaft 64 between the standards 62, 63, is operatively connected to the punch head 58 in the usual manner by means of a link. A countershaft 94, journaled in the uprights 62, 63 in rear of the 35 drive shaft 64 and having gear connection 95, 96 therewith, whereby it turns at the same rate as the drive shaft but in the opposite direction, serves for transmitting motion to certain other parts of the machine. 40 The die-block 59 is supported by the uprights 62, 63 above the table 54, the blanks a cut from the stock X by the movement of the punch head 58 into the die-block 59 being delivered onto the table 54 through the 45 die aperture. For insuring the downward movement of the blanks a through the die-block 59, a pair of electro-magnets 67, set into the table 54 through the bed plate 98, and having pole pieces located in line with 50 the aperture of the die-block 59, are preferably provided. As shown, these electro-magnets are supported by a bracket 68, secured to the underside of the bed plate 98, and their coils are in circuit with a battery, 55 diagrammatically represented at 69 (Fig. 4), and with a switch, generally designated by the numeral 70, controlled by the punch head. The switch 70 is shown in detail in Fig. 20 of the drawings. It preferably comprises a pair of insulated terminal blocks 60 71, 72, mounted on the standard 62, adjacent the punch head 58. One of the terminal blocks, as 71, is of T-shape, and the other terminal block 72 is a two-part mem- 65 ber comprising a base 73 fixed in position on

the standard 62, and an L-shaped contact-piece 74, adjustably secured in position by means of set-screws 75, which enter the base-block 73 through a slotted aperture 76 in the longer leg of the L-shaped contact-piece 70 74. A bridge-piece 77 is carried by the punch head 58 for connecting the terminals 71, 72. As shown, this bridge-piece is of spring metal and of flattened U-shape, one of the arms 78 of the U being in continuous 75 sliding contact with the widened T-head of the terminal block 71, and the other arm 79 of the U being movable into and out of engagement with the shorter leg of the adjustable L-shaped member 74 of the terminal 80 72 by the movement of the punch-head.

A supplemental work-table 80 is provided for supporting the stock X as it is delivered to the punch A. As shown, this work-table 85 is supported at one of its ends by the table 54 to which it is secured by set screws 99 (Fig. 5) and at the other end by a bracket 81 which rises from the bed-plate 98. The work-table 80 carries feed mechanism generally designated by the numeral 82 for advancing the work upon the punch A. The mechanism 82 comprises a cross head which is mounted in slideways 83 provided in the work-table 80, and carries a spring clamp 84 95 for gripping the work. A rack bar 85 is rigidly secured to the cross head of the feed mechanism, 82, and extends forwardly therefrom beneath the work table 80. For moving the rack bar 85, a rock shaft 86 extends 100 transversely beneath the work table 80, and is journaled in bearing blocks 87, mounted on the bed plate 98. A crank arm 88, mounted on the rock shaft 86, carries a spring pawl 89 adapted to operatively engage the rack bar 85 when the rock shaft 86 turns in one direction. The rock shaft 86 is oscillated between each movement of the punch head 58. For this purpose, as shown, it is provided with a crank-arm 90, 105 which is connected by a link 91 with a crank pin 92, adjustably mounted in a crank disk 93 formed upon the end of the countershaft 94. A table 100 (Figs. 5 and 15) is supported over the table 54 in rear of the die-block 59 for receiving that which remains of the stock, as the mutilated sheet illustrated in Fig. 30, after it passes the punch A. The dies B, C, D, E, F, G, and H operate in succession upon the head 50 of the 110 blank a (Fig. 21). For that purpose they are preferably located along one side of the table 54 at different distances from the punch A, as most clearly shown in Figs. 1 and 15, and feed mechanism having an intermittent movement is provided for causing the blanks a to travel along the table in front of the dies. The die I operates upon the strap portion 51 of the blank a adjacent its outer end, and for that purpose it is 115 120 125 130

preferably located upon the other side of the table 54 from the dies just mentioned. As shown, it is located beyond the die H from the punch A.

- 5 The feed mechanism for moving the blanks *a* along the table 54 most desirably comprises a pair of reciprocating bars 101 and 102, most clearly shown in Figs. 15 and 16. These bars preferably extend from a 10 point below the die-block 59 of the punch A where the blanks *a* cut by the punch are received upon the table 54, to the rear end of the table 54 (Fig. 3) beyond the die I and the numbering mechanism J, where the 15 blanks *a* are discharged by gravity in the form of finished seals (Fig. 29). As shown, the bars 101, 102 are embedded in the surface of the table 54 by being laid into correspondingly formed grooves or slide- 20 ways which extend along the table from end to end. Each of the bars has formed therein a longitudinal slot 103, and within this slot are mounted a plurality of spring pawls 104. The pawls 104 are mounted to 25 swing in a vertical plane, each of them, as shown, being pivoted upon a pin 105 which is set transversely through the corresponding bar 101, 102, and crosses the slot 103. The forward end of each pawl is urged up- 30 wardly to yieldingly project above the surface of the table 54, as by means of a spring 106, which reacts between the free end of the pawl and the floor of the slot 103. Preferably the pawls 104 are located at intervals 35 along the bars 101, 102, corresponding to the distance through which the blanks *a* are to be moved along the table 54 upon each reciprocation of the feed bars, and stops 117 are provided for preventing a return move- 40 ment of the blanks on the table. For reciprocating the feed bars 101, 102, each is provided with a lug 107 (Figs. 1 and 13) which extends below the table 54 through a slot 108. A rock shaft 109 extends trans- 45 versely beneath the table 54 and is journaled in brackets 110 secured to the under side of the table. This rock shaft is preferably oscillated between each movement of the punch head 58. For that purpose a crank 50 arm 111, located at one side of the table 54 and mounted upon the end of the rock shaft 109, is connected by a link 112 with a crank pin 113 adjustably mounted in a crank disk 114 formed upon the end of the drive shaft 55 64. Crank arms, as 115, are mounted on the rock shaft 109 below the table 54 and in line with each of the lugs 107. Each of these crank arms is operatively connected to one of the lugs 107 by an adjustable link 116. 60 The stops 117 for preventing backward movement of the blanks *a* on the table 54 are preferably arranged in a double row and at intervals throughout the length of the table corresponding to the spacing of 65 the pawls 104 carried by the feed bars 101,

102. Most desirably these stops are vertically movable, being raised by contact therewith of the advancing blanks to permit the blanks to pass beneath them while they fall by gravity in rear of the blanks to 70 prevent backward movement of them. As shown, two slightly different forms of the stops are employed upon the machine, the form illustrated in detail in Figs. 5, 15 and 16 being used throughout the greater por- 75 tion of the length of the table 54, while another form illustrated in Figs. 1 and 3 is employed adjacent the rear end of the table 54 for controlling the movement of the blanks *a* as they pass the numbering mechanism J. 80 The first-mentioned form comprises a pair of bars 118, 119 which extend over the table 54 from its forward end to a point just in front of the numbering mechanism J. These bars are supported in a vertical plane 85 by brackets, as 120, 121 located at intervals along the table 54. The bars 118, 119 are attached to these brackets in such a way as to permit vertical movement of the bars, as by means of bolts 122, which pass through 90 the bars and through vertically slotted apertures 123 in the brackets. The weight of the bars 118, 119 is received by the blanks *a* upon the table 54, and the stops 117 preferably take the form of gravity pawls 124 95 pivotally secured at one end to the corresponding bar, as 118, 119, and having their free ends resting upon the table 54. Adjacent the rear end of the table 54, the stops 117 take the form of shoulders formed upon 100 bars 125, 126 (Figs. 1 and 3) which extend over the table 54 and are supported for movement in a vertical plane, after the manner of supporting the bars 118, 119, by brackets, as 127, 128. In order to provide 105 space for the numbering dies J between the feed bars 101, 102, one of these bars, as 102, is offset adjacent its rear end, as shown at 129, (Fig. 3).

Pressure in addition to that placed upon 110 the blanks *a* by the bars 118, 119, and 125, 126, as the blanks move along the table, is applied at intervals by means of pressure bars 132, 133. These pressure bars, as shown, are attached to overhanging brackets 115 134, 135 by screw bolts 136 which enter a slotted aperture 137 in the corresponding bracket. The weight of the pressure bars 132, 133 is supplemented by means of springs 138 which react between the bars adjacent 120 each end and a cross arm 139 carried by the brackets, as 134, 135. Guides 140 which, as shown, take the form of angle irons applied to the surface of the table 54, extend along the table adjacent its margins for 125 engaging the ends of the blanks *a*. The brackets 134, 135 rise from the table 54 at a point outside of the guides 140.

For supporting the dies B, C, D, E, F, G and H, a ledge or flange 130 preferably ex- 130

tends along one side of the table 54 throughout a portion of its length. As shown, the ledge or flange 130 is permanently secured to the table 54 adjacent its edge, as by screw bolts 131 (Fig. 8). The flange 130 also serves for supporting the brackets 120, to which the bar 118 is attached. A cam shaft 141 extends alongside of the table 54 for operating the dies B, C, D, E, F, G, H and I and the numbering apparatus J. As shown, this cam shaft is journaled in brackets 142 formed upon the flange plate 130, and it is rotated at the same rate as the drive shaft 64, by being operatively connected to the countershaft 94 through an intermediate vertical shaft 143 (Figs. 2 and 5), which has bevel gear connection 144, 145 with the countershaft and the cam shaft.

The die B is a simple punch for punching an aperture in the blanks α adjacent the head 50, as shown at b , Fig. 22. It comprises a vertically-movable punch-head 146 and a coöperating apertured die plate 147 (Fig. 15). The punch head 146 is mounted in slideways 148 formed upon a bracket plate 149 secured to the flange plate 130, as by screw bolts 150, and the die plate 147 is mounted in the table 54 in such a way that the blanks α are moved over it by the feed bars 101, 102 and the coöperating stops 117. For reciprocating the punch head 146 a lever 151 is pivotally attached at 152 to the end of the flange plate 130 (Fig. 2). This lever has a lug 153 formed upon one end, which enters a notch 154 in the side face of the punch head 146. The other end of the lever 151 carries a cam roller 155 which co-operates with a cam 156 (Fig. 13) mounted on the cam shaft 141. The cam roller 155 is held in coöperating relation with the cam 156 by means of a spring 157 which bears downwardly on the lever 151, as by being coiled about a spindle 158 having a yoke 159 at one end which is attached to the lever 151, and having its other end slidingly mounted in a bracket plate 160 secured to the flange plate 130, as by a screw bolt 161. The spring 157 reacts between the under side of the bracket plate 160 and the yoke 159.

A feature of the seal illustrated in Fig. 29 of the drawings is a barbed tongue 162 inclosed within the head of the seal and formed upon the end of the blank α (Fig. 21). The function of the die C is to fold the tongue 162 to the position illustrated at c , Fig. 23. To this end the die C is preferably located beyond the die B from the punch A in a position to engage the blank after it has been operated upon by the punch B during its movement along the table 54. As most clearly shown, in Fig. 13 of the drawings, the die C comprises a stationary shoe or anvil 163, adjustably supported over the table 54, as by a bracket 164, secured to the flange plate 130. Preferably the bracket

164 extends between ways 165 formed on the flange plate 130 and is secured in adjusted position by means of a clamping bolt 166 which enters the flange plate 130 through a vertically slotted opening 167 in the bracket. 70

The anvil 163 has a lateral projecting foot-piece 168, and the tongue 162 is folded upwardly over the foot piece 168 by means of a die-finger 169 which has in turn an upward and a forward movement through a slotted opening 170 in the table 54. As shown, the finger 169 is carried by a rocking member 171, pivotally secured at 172 to lugs 173 formed upon the lower edge of the flange plate 130. The rocking member 171 carries a cam-engaging roller 174, and this roller coöperates with a cam 175 mounted on the cam shaft 141 for raising the die-finger 169. For permitting the forward movement of the die-finger 169 it has a sliding connection with the rocking member 171, as by means of bolts 176 which enter the rocking member 171 through a slot 177 in the finger. The finger 169 is normally retracted by a spring 178 which reacts between a bracket member 179 secured to one of the bearing blocks 142 of the cam shaft 141 (Fig. 2), and a plunger rod 180 connected to the finger. A cam 182 mounted on the cam shaft 141 serves for advancing the die finger 169, as by engaging an upwardly projecting shoe or heel 181 formed upon the finger at its rear end. Preferably the cams 175 and 182 are so proportioned and relatively disposed upon the cam shaft 141 that the forward end of the die finger 169 is raised by the cam 175 prior to being advanced by the cam 182 and is maintained in the elevated position until the cam 182 has passed the shoe 181 and the finger has been again retracted by the spring 178. The die finger 169 thus serves to fold the tongue 162 over upon the projecting heel 168 of the anvil 163, and by pressing it against the concave face 168a of the anvil, gives it the curved form illustrated in Fig. 23. When the die finger has been withdrawn from contact with the tongue, it is lowered to the normal position illustrated in Fig. 13, by a spring 232 which bears upwardly on the rear end of the rocker member 171, as by being coiled about a plunger 233 pivotally connected to the rocker member and sliding through a bracket 234, the said spring reacting between the bracket and a shoulder 235 formed on the plunger. 110

The function of the die D is to change the blank α from the flat form illustrated in Figs. 21, 22 and 23 of the drawings, to the form shown at d (Fig. 24), wherein the widened portions 183 and 184 of the head 50 of the blank are provided with complementary flanges capable of being interfolded to form the side seams 236, 237 of the head of the seal (Fig. 29). Preferably this die also 125

strikes a pocket 185 in the part 183 of the blank *a* and depresses the tongue 162 from the inclined position shown at *c* in Fig. 23 to the position illustrated in Fig. 24.

5 As shown, the die D comprises a vertical movable punch head 186 supported over the table 54 and a coöperating die plate 187 embedded in the table. These parts are most clearly illustrated in Figs. 14 and 15 of the 10 drawings. The blank *a* is moved over the die plate 187 during its step by step advance along the table 54 after it passes the die C. The punch head 186 is preferably mounted for vertically sliding movement in 15 slideways 188 formed in a bracket plate 189 which is permanently secured to the flange plate 130. The punch head 186 is operated from the cam shaft 141 through a lever 190. As shown, this lever has a rounded head 191 which projects through a slotted opening 192 in the flange plate 130 into a pocket 193 provided in the punch head.

For pivotally supporting the lever 190, bearing blocks 194 are applied to the outer 25 face of the flange plate 130 and are adjustably secured thereon by means of screw bolts 195 and set screws 196. The set screws 196 have a threaded bearing in an overhanging lip 197 provided upon the upper edge of the 30 flange plate 130, and resist upward pressure on the bearing blocks 194. At the outer end of the lever 190 is mounted a cam-engaging roller 198 which coöperates with a cam 199 mounted on the cam shaft 141 for depressing 35 the punch head 186. For raising the punch head 186 a spring 200 is preferably employed. As shown, this spring is coiled about a rod 201 having its lower end connected to the lever 190 while its upper end 40 has a sliding bearing in a bracket arm 202 secured to the flange plate 130 by a screw bolt 203. The spring 200 reacts between the under side of the bracket arm 202 and a shoulder 204 formed on the rod 201.

45 The punch head 186 and die plate 187 have complementary formed die faces and each is preferably also provided with spring-advanced strippers 205, 206, the former being designed to prevent the blank 50 *a* from being raised from the table 54 by the punch head 86 and the latter being adapted to raise the formed blank out of the depressions of the die plate 187 in order that its movement along the table 54 upon 55 the next advance of the feed bars 101, 102 will not be interfered with.

The die E is most clearly illustrated in 60 Figs. 6, 10 and 11 of the drawings. The function of this die is to fold the outer portion 184 of the head 50 of the blank *a* over upon the inner portion 183 in the manner shown at *e*, Fig. 25. Preferably this die is generally similar in construction to that 65 designated C and heretofore described, the anvil member about which the folding op-

eration is performed being, however, in this instance, a movable member in order that it may be entered between the upstanding flanges formed on the portion 183 of the blank *a* by the die D after the blank has 70 been positioned in front of this die by the movement of the feed bars 101, 102.

As shown, the anvil about which the folding of the blank *a* is accomplished by the die E takes the form of a hook-shaped member 207 pivotally supported at its higher 75 end from a bracket 208 secured to the inside face of the flange plate 130. The movement of the member 207 is controlled by a cam 212 mounted on the cam shaft 141. 80 A jointed link 209 is pivotally connected to the member 207 at 210 and extends outwardly through a slotted opening 211 in the flange plate 130 to operatively engage this cam. Preferably the outer section 213 of 85 the jointed link 209 is curved, and straddles the cam 212 to be moved thereby in opposite directions. As shown, cam-engaging rollers 214, 215 are provided at the two ends of the 90 curved section 213 of the link 209. These rollers are maintained in coöperative relation with the cam by means of a spring 216 which bears downwardly on the member 213. Most conveniently the spring 216 is coiled 95 about a rod 217 which has a sliding bearing in a bracket arm 218 carried by the flange plate 130 and is connected at its lower end to the member 213. A die finger 219 having in turn an upward and a forward movement is employed for folding the parts of 100 the blank *a* about the hooked end of the anvil member 207 when the latter has been advanced to the position shown by dotted lines in Fig. 10. This die finger is similar 105 in construction and operation to the die finger 169 employed for folding the barbed tongue 162, and will not be further described.

The die F is shown in detail in Figs. 6, 9, 33 and 34. The function of this die is to fold 110 the upturned edges of the part 183 of the blank *a* over upon the side edges of the part 184 in the manner shown at *f* Fig. 26, to form the side seams of the chambered head of the seal. To this end the die F comprises yielding clamping members adapted 115 to compress the parts 183, 184, of the blank *a* together without the use of sufficient force to distort them, and laterally movable die members for folding in the upturned edges 120 of the part 183.

As shown, the clamping members comprise a yielding base block 220 set in the table 54 in such a position that the folded parts 183, 184, of the blank *a* are moved 125 into register with it by the advance of the feed bars 101, 102, after having passed the die E. The table 54 is provided with an aperture 221, Fig. 9, for receiving the block 220, and a bracket plate 222 is secured to 130

the under side of the table to provide a support for the block. Preferably the block 220 is seated upon springs 223, Fig. 6, which bear upon the bracket plate 222, these 5 springs, as shown, being coiled about set screws 224, which are mounted in the bracket plate 222, and serve as adjustable stops for limiting the downward movement of the block 220. The face of the block 220 10 is recessed, as shown at 225, Fig. 34, to provide a seat for the pocket 185, formed in the part 183 of the blank *a* by the die D, and its side edges are rabbeted, as shown at 226, 227, to provide bearing shoulders against 15 which the side edges of the blank may be folded. Stripper members 228, 229, are provided for raising the blank clear of the die block 220, after the folding. As shown, 20 these stripper members take the form of vertically movable plungers set into the block 220 and normally supported in a position in which their higher ends project above the face of the block by springs, as 25 230, Fig. 9, which react between the lower ends of the plungers and the bracket plate 222.

A vertically movable plunger 231 coöperates with the yieldingly supported block 220 30 for pressing the parts 183, 184, of the blank together without distorting them. This plunger has a smooth under surface 232 adapted to bear upon the part 184 of the blank *a*, Fig. 26. As shown, the plunger 231 is mounted in vertical slideways 233, 35 formed upon the flange 130, and it is operated by a cam 234 mounted on the cam shaft 141, by means identical with that employed for operating the punch head 186 of the die D, Fig. 14, and which need not, therefore, 40 be further described.

Laterally movable die members 235, 236, Fig. 6, are employed for coöperating with the rabbeted shoulders 226, 227, formed on the block 220 for folding the upturned side 45 edges of the part 183 of the blank *a* onto the edges of the part 184 of the blank when these parts have been pressed together by downward movement of the plunger 231. As shown, the cam 234 is so formed as to retain the plunger 231 in its lowered position 50 during the operation of the die members 235, 236. These die members are formed upon the higher ends of swinging levers 237, 238, each of which is pivotally supported intermediate its ends upon an adjustable bearing block 239, secured to the under side of the table 54, as by a clamping bolt 240, which enters the table through a slotted 55 opening 241, in the bearing block. Set screws 242, mounted in flanges 243, formed upon the under side of the table 54, serve for adjusting the position of the bearing blocks 239, when the clamping bolts 240 are loosened.

60 Each of the levers 237, 238, is provided

with a cam-engaging roller 244 at its lower end, and a wedge-shaped cam 245, adapted to move upwardly between the rollers 244, is provided for swinging the levers. As shown, the cam 245 is formed upon a lever 70 246, which is pivoted, at 247, to swing in a vertical plane. The pivot 247 is conveniently supported by a bracket 248, secured to the under side of the table 54. Preferably the movement of the cam 245 between the rollers 244 is positively guided. For this purpose a guideway 249 is mounted upon the under side of the table 54, as by being secured to a flange or rib 250 formed thereon, for receiving the forward end of 80 the lever 246. The rear end of the lever 246 is provided with a cam-engaging roller 251, which coöperates with a cam 252 mounted on the cam shaft 141, for swinging the lever. A spring 253, coiled about a plunger 254, 85 secured to the lever 246 and reacting between a bracket 255, secured to the under side of the table 54, and a shoulder 256, formed on the plunger, serves for maintaining the roller 251 in operative engagement 90 with the cam 252. For maintaining the die members 235, 236 normally separated, a spring 257 reacts between the levers 237, 238, adjacent their lower ends.

The die G is illustrated in detail in Figs. 95 7, 8, 35 and 36. The function of this die is to turn the side seams formed upon the head of the blank *a* by the die F, as shown at *f*, Fig. 26 of the drawings, to the inclined positions shown at *g*, Fig. 27. For this 100 purpose a stationary die block 258, Fig. 36, is provided. This die block has a central aperture 259 of less width than the head of the blank *a*, as illustrated in Fig. 36 of the drawings, and the bending of the side seams 105 of the blank *a* in the manner just described is effected by forcing the head of the blank into the aperture. In order that this may be effected without crushing in the walls of the chambered head of the blank, a punch 110 member 260, having marginal extensions 261, 262, adapted to span the body portion of the head of the blank and engage the side seams thereof adjacent their inner edges, is employed.

115 As most clearly shown in Fig. 7 of the drawings, the die block 258 is rigidly mounted in the table 54, and the punch member 260 has a vertical sliding movement over the die block by being mounted in slideways 263, formed on the flange 130. The punch member 260 is operated by a cam 264 mounted on the cam shaft 141, through mechanism identical with that provided for operating the punch member 186 120 of the die D, illustrated in Fig. 13 of the drawings, and will not be here described. An anvil block 265 is yieldingly mounted within the central aperture 259 of the die block 258. As shown, a bracket plate 266 125

130

is secured to the under side of the table 54 below the die block 258 and has a socket 267 which registers with the aperture 259. Within this socket is adjustably mounted 5 an abutment 268. As shown, the abutment 268 is supported in the desired position of adjustment by a set screw 269, mounted in the bracket plate 266, and entering the socket 267. This abutment provides a cushioned 10 seat for the anvil block 265, as by having mounted thereon a block 270 of resilient material, such as rubber. A spring-advanced stripping plunger 271, is mounted in the punch member 260 for preventing 15 the blank *a* from being raised with the punch after it has been struck by it, and plungers 272, 273, are mounted in the die block 258 for normally supporting the blank *a* clear of the die. The plungers 272, 273, 20 are mounted in recesses 274, 275, respectively, formed in the walls of the die block 258. Each of these plungers has a stem 276 upon its lower end, and about this stem is coiled a spring 277, which reacts 25 upon the base of the anvil block 265, to yieldingly project the higher end of the plunger above the die block 258.

The die H is generally similar in construction to the die F, and has for its function to set the fold of the side seams of the head of the blank *a*, begun by the die G, as shown at *g*, Fig. 27, to the vertical positions shown at *h*, Fig. 28. For this purpose plunger and anvil block members, designated 30 278, 279, respectively, are provided for gripping the body portion of the head of the seal without distorting its walls. The plunger 278 is identical in construction and operation with the plunger member 231, 35 of the die F, and will not be further described. As most clearly shown in Fig. 28 of the drawings, the folded edges 280, 281, of the side seams of the head of the blank *a*, project below the body portion of the part 40 183 of the blank. To serve as an abutment against which these folded edges may be set, the anvil block 279 is of such size that it engages the body portion of the part 183 of the blank, while permitting the edges 45 50 of the side seams to overhang its margins. In other respects the anvil block 279, as shown, is identical in construction with the anvil block 220 of the die F, Fig. 6, and is yieldingly supported in the same manner. 55 Hammers 282, 283, having lateral movement, are provided for striking the side seams of the head of the seal when it is gripped between the anvil block 279 and the plunger 278, the side faces of the anvil 60 65 block 279 then serving as abutments against which the hammers react in setting these side seams. As shown, the hammers 282, 283, are mounted upon the higher ends of the levers 284, 285, respectively. These levers are preferably supported in the same

manner as the levers 237, 238, of the die mechanism F, Fig. 6, and they are operated by a cam 286 mounted on the cam shaft 141, Fig. 3, through the medium of a vertical swinging lever 287. As shown, the lever 287 is identical in construction and operation with the lever 246, employed for swinging the members 237, 238 of the die mechanism F, Figs. 6 and 9.

The operation of the die H completes the 75 formation of the head of the seal shown in Fig. 29 of the drawings, and in the use of the machine organized as herein described there now remains merely the formation of apertures 288, 289 in the strap portion of 80 the seal. As shown, the aperture 288 co-operates with the barbed tongue 162 for locking the end of the strap in position when it is inserted in the head of the seal, and for this purpose it is provided with a marginal flange 290. The apertures 288, 289, and the flange 290 are formed in the die mechanism generally designated I. The parts of this die mechanism are most clearly shewn in Figs. 3 and 12 of the drawings. 85 It includes punching tools 291, 292, and a die block 293 embedded in the table 54, for simultaneously cutting the apertures 288, 289, one of the punching tools, as 292, being provided with an inclined blunt end for 90 striking up the flange 290 at the margin of the aperture 288. Preferably the punching tools 291, 292, are mounted upon the end of a punch head 294, having a vertical sliding movement in a standard, as 295, 100 which rises from the table 54. A bell crank lever 296, pivotally mounted between bearing lugs 297, 298, formed on the standard 295, serves for imparting motion to the punch head 294, from the cam shaft 141. As 105 shewn, the punch head 294 is provided with a socket 299, and a rounded bead 300, formed on the shorter arm of the bell crank lever 296, enters this socket. The longer arm 301 of the bell crank lever 296 is connected by a link 302 with cam mechanism 110 generally designated 303, and including a cam 304 mounted on the cam shaft 141. Preferably the link 302 is adjustably connected to the bell crank lever 296, as by 115 means of a clamping bolt 305, which runs in a slot 306 formed in the arm 301. The link 302 has a reciprocating movement and the cam mechanism 303 is preferably a form of eccentric and strap, whereby the link is positively moved in each direction. As shown, this cam mechanism comprises a chambered casing 307 secured to the end of the link 302 and inclosing the cam 304. 120

The mechanism J for stamping words 125 and numerals on the strap portion 51 of the blank *a* intermediate its ends, may be of any well known form of construction and is not here shown in detail. It is preferably operated by means of a counter shaft 130.

308, which extends transversely beneath the table 54, and is journaled in hangers, as 309, depending from the table. As shown, this counter shaft is operatively connected by 5 gears, as 310, 311, with a vertical shaft 312. At the higher end of the vertical shaft 312 there is mounted a bevel gear 313, which operatively engages a bevel gear 314 loosely mounted on the shaft 141, and adapted to be 10 rotatably connected therewith by means of a clutch 315. In order that the operation of the numbering dies J may be interrupted from time to time, as when the machine is first set in motion, and blanks *a* being advanced along the table by the feed bars 101, 102, have not yet reached these dies, the clutch 315 is preferably manually controlled, as by means of a shifter lever 316 pivotally connected at 317 to a bracket 318 15 secured to the flange plate 130.

Provision is desirably made for collecting the finished seals produced by the machine in bundles containing a definite number. As shown, a tray 319 is supported by the 20 standard 57 below the discharge end of the table 54, and a plurality of racks 320, each of which may be conveniently made of the form illustrated in Fig. 32 of the drawings, are employed on the tray 319 for receiving 25 the seals as they fall from the table. Each of the racks 320, comprises a base plate 321, and spindles 322, 323, 324, rising therefrom, the arrangement being such that the seals, in falling from the table, will be automatically 30 threaded upon the spindle 322, while the head ends of the seals will fall between the spindles 323, 324. The higher end of the spindle 322 is provided with an eye 325, into which a wire or cord (not shown) may 35 be threaded to serve as a connector for uniting the seals in bundles when they are removed from the rack.

Mechanism is preferably provided for automatically positioning the racks 320 on the 40 tray 319 to receive a predetermined number of seals in the manner just described. As shown, a guide plate 326 is movably supported over the tray 319. Preferably this guide plate is hung upon the end of a slide 45 bar 327, which has a sliding bearing upon the under side of the table 54, and is normally retracted by a spring 328. The guide plate 326 and tray 319 are so positioned with reference to the discharge end of the 50 table 54, that if a plurality of the racks 320 are laid upon the tray in front of the guide plate when the latter is in its retracted position, one of these racks remote from the guide plate will be properly located to receive 55 the seals as they fall from the end of the table 54, while the advance of the guide plate will move the racks along the tray to locate the next adjacent rack in the receiving position. Upon the return of the guide 60 plate to its retracted position, an attendant 65

may interpose an additional rack between the guide plate and the racks already on the tray, whereupon the operation of shifting the racks will be again automatically effected at the next advance of the guide 70 plate.

Mechanism for automatically shifting the guide plate 326, at predetermined intervals is provided, and in order that this mechanism may only be operated when seals are 75 being delivered from the end of the table 54, this mechanism is preferably actuated by operative parts of the machine controlled by the clutch 315, as the counter shaft 308. As shown, an arm 329 is pivotally supported 80 upon the standard 57 at 330, and this arm carries a roller 331 which coöperates with a cam 332, mounted on the counter shaft. For maintaining the roller 331 in engagement with the cam 332, a spring 333 reacts 85 between the higher end of the arm 329 and a fixed support, as a bracket member 334, secured to the table 54. A disk 335 is rotatably mounted upon the pivot 330 of the arm 329. Upon the periphery of this disk is 90 formed a series of notches 336, equal in number to the number of seals desired in each package. One of the peripheral notches, as 337, of the disk 335, is of greater depth than the others, and a pawl 338 carried by the 95 arm 329, coöperates with the notches 336 for turning the disk. A plunger 339 is pivotally connected to the arm 329 above the pawl 338, and normally moves over the 100 guide plate 326. This plunger is operatively connected to the pawl 338 by means of a link 340, the length of the link 340 being such that when the pawl 338 falls into the deep notch 337, the plunger 339 is lowered to engage the guide plate. A spring 341 105 reacting between the arm 329 and the link 340, serves for maintaining the pawl 338 in operative engagement with the periphery of the disk 335. Preferably the drive shaft 64 is turned by a belt pulley 342, loosely 110 mounted thereon, and adapted to be rotatably connected with the drive shaft by clutch mechanism, such as that illustrated in Figs. 17, 18, 19, of the drawings. As shown, the belt pulley 342 is mounted upon a part 343 115 of the drive shaft 64, which is of reduced diameter. The hub of the belt pulley 342 has a plurality of sockets 344, Fig. 18, formed therein, and a spring bolt 345 is mounted in the drive shaft for entering the 120 sockets 344.

The following described mechanism may be employed for controlling the spring bolt 345: A circumferential groove 346 is formed in the drive shaft 64, and the spring bolt 125 345 crosses this groove. A wedge block 347 is adapted to enter the groove for engaging the spring bolt 345 to retract it. As shown, the spring bolt 345 has a cam 348 in line with the groove, and this cam slot coöperates 130

with the wedge block 347. The wedge block 347 is spring-advanced, and a pedal 349 is provided for withdrawing it when it is desired to set the machine in motion. A latch 5 is provided for holding the wedge block in the retracted position when the pedal 349 has been depressed, and provision is made for automatically releasing the latch to arrest the movement of the machine when a sheet of tin stock X has been completely passed beneath the punch A. As shown, the wedge block 347 is provided with a stem 350, slidingly mounted in bearing lugs 351, formed upon the standards 63, and a spring 15 352 coiled about the stem 350 reacts between one of the bearing lugs 351, and a shoulder 353 formed on the stem to advance the wedge block. The stem 350 of the wedge block 347 and the pedal 349, are connected by a link 354. A latching bolt 355, having a sliding bearing in the standard 63, co-operates with a shoulder 357 formed on the stem 350 of the wedge block 347, to hold the latter in retracted position. This latching bolt 20 is advanced by a lever 359 which bears upon the head of the bolt and is withdrawn by a spring 360, coiled about the bolt, when the lever 359 is raised. The lever 359 is pivotally mounted upon a bracket 361 secured to 25 the standard 63, and extends downwardly adjacent the standard to a position at the side of the work table 83. A spring 358, of greater power than the spring 360, reacts between the lever 359 and a fixed support, as 30 the standard 63, to normally cause the lever to bear upon the head of the latching bolt. For raising the lever from the head of the bolt, a bell crank lever 362 adapted to be 35 engaged by an appurtenance of the mechanism employed for advancing the sheets of 40 tin stock X upon the punch A, is provided.

As shown, the bell crank lever 362 is pivotally secured to the under side of the supplemental work table 80, as at 364, Figs. 2 45 and 4, and one arm of the bell crank extends into the path of a trip 363 carried by the rack bar 85. As the rack bar 85 approaches the end of its forward movement, the trip 363 engages the bell-crank lever 362 and 50 turns it to the left, as viewed in Fig. 2, thus throwing the lever 359 out of engagement with the head of the latching bolt 355, whereupon this bolt is withdrawn from engagement with the shoulder 357 formed on 55 the stem 355 of the wedge-block 347 and the latter is raised by the spring 352.

In the use of the machine a sheet of tin stock is laid flat upon the work table 80 in front of the clamp 84 when the latter is in 60 a retracted position, and the clamp is manually adjusted to grip the rear edge of the stock. The treadle 349 is then depressed to withdraw the wedge block 347 from engagement with the cam groove 348 of the spring 65 bolt 345, thus permitting the latter to be pro-

jected by its spring into one of the sockets 344 of the drive pulley 342. The machine is thus set in motion and the sheet of tin stock is advanced beneath the punch 58 by a step by step movement by reason of the 70 oscillation of the rock shaft 86 and engagement of the pawl 89 with the rack bar 85, to which the grip 84 engaging the sheet of tin stock is attached. Upon each stroke of the punch 58 a blank of the form shown at a (Fig. 21) is cut from the stock and falls through the die aperture of the die-block 59 on to the table 54. The electro-magnets 67 attract the sheet metal blank a to insure its passage through the aperture of the die block 59 and to cause it to lie flat upon the surface of the table 54 beneath the die block, in order that it will be engaged by the pawls 104 of the reciprocating feed bars 101, 102. These pawls, by co-operation with the stop 75 fingers 117, advance the blank along the table by a step by step movement, and during this movement the blank is engaged successively by the dies B, C, D, E, F, G, H and I, respectively, and by the numbering mechanism J. After passing the numbering mechanism the blank, which by this time has assumed the form shown in Fig. 29 by reason of the operation of the several dies upon it, is pushed off the end of the table 54 and falls 80 onto one of the racks 320 located on the shelf 319 (Fig. 31). The several cams mounted upon the cam shaft 141 are so positioned that the several dies B, C, D, E, F, G, H and I, and the numbering mechanism J are operated simultaneously during the return movement of the feed bars 101, 102, whereby the blanks are at rest upon the surface of the table 54 because they are held against rearward movement by the stop fingers 117. 85 This action is continued until the trip 363 (Fig. 2) reaches the bell-crank lever 362. At this time the repeated operations of the punch 58 have reduced the sheet of tin stock to the mutilated form shown by full lines in 90 Fig. 30. The parts are now automatically brought to rest in the manner heretofore described, by the turning of the bell-crank lever 362 and the swinging of the lever 359 (Fig. 4) out of engagement with the head 95 of the bolt 355. The pawl 89 (Fig. 1) is now manually released from the rack bar 85 and the rack bar and clamp 84 are manually drawn back to their initial position by grasping the clamp. The mutilated sheet of 100 tin stock may then be released from the clamp 84, and when either a new sheet of tin stock, or the mutilated sheet turned end for end has been adjusted in the clamp, the parts 105 are again set in motion by depressing the treadle 349. 110

I claim as my invention:—

1. In a sheet metal working machine, in combination, co-operating punch and die block members, the punch-receiving aper- 115

ture of the die block being extended through the block, and a magnet located beyond the block in line with the said aperture.

2. In a sheet metal working machine, in combination, coöperating punch and die block members, the punch-receiving aperture of the die block being extended through the block, an electro-magnet located beyond the block in line with the said aperture and a switch in circuit with the electro-magnet controlled by the punch.

3. In a sheet metal working machine, in combination, a work table, feed mechanism for moving sheet metal blanks along the table, a die block supported over the table having a die aperture extending through the block, a punch movable downwardly into the die aperture of the block, and a magnet below the table in line with the die aperture.

20 4. In a sheet metal working machine, in combination, a work table, feed mechanism for moving sheet metal blanks along the table, a die block supported over the table having a die aperture extending through the block, a punch movable downwardly into the die aperture of the block, an electro-magnet below the table in line with the die aperture, and a switch in circuit with the electro-magnet controlled by the punch.

30 5. In a sheet metal working machine, in combination, a blank-cutting die and a sheet metal forming die, feed mechanism receiving from the blank-cutting die and delivering to the sheet metal forming die, unitary driving means operating both of the said dies and the said feed mechanism, a clutch controlling the said driving means, feed mechanism for sheets of stock delivering to the blank-cutting die, and a clutch-shifting 35 trip carried by the last named feed mechanism.

6. In a sheet metal working machine, in combination, a work table, a pressure bar extending over the table adapted to bear upon articles on the table, a series of stop lugs on the bar, and feed mechanism having an intermittent movement coöperating with the said stop lugs to give the said articles a step-by-step movement along the table.

50 7. In a sheet metal working machine, in combination, a work table, a pressure bar extending over the table adapted to bear upon articles on the table, a series of pivoted gravity pawls carried by the bar and having 55 their free ends resting on the table, and feed mechanism having an intermittent movement coöperating with the said pawls to give the said articles a step-by-step movement along the table.

60 8. In a sheet metal working machine, in combination, a work table having a longitudinal channel, a bar slidingly mounted in the channel of the table, the top of the bar being substantially flush with the surface 65 of the table, a series of spring pawls car-

ried by the bar, each of said pawls having an abrupt forward face and an inclined rearward face normally projecting above the surface of the table, a pressure bar extending over the table adapted to bear upon articles on the table, a series of stop lugs on the pressure bar, and means for reciprocating the first-named bar.

70 9. In a sheet metal working machine, in combination, a work table having a longitudinal channel, a channeled bar slidingly mounted in the channel of the table, the edges of the bar being substantially flush with the surface of the table, a series of spring pawls pivotally mounted in the channel of the bar, each of said pawls having an abrupt forward face and an inclined rearward face normally projecting above the edges of the bar, a pressure bar extending over the table adapted to bear upon articles 80 on the table, a series of stop lugs on the pressure bar, and means for reciprocating the first-named bar.

85 10. In a sheet metal working machine, in combination, a work table having a longitudinal channel, a channeled bar mounted in the channel of the table, the edges of the bar being substantially flush with the surface of the table, a series of spring pawls pivotally mounted in the channel of the bar, 90 each of said pawls having an abrupt forward face and an inclined rearward face normally projecting above the edges of the bar, a bar extending longitudinally over the table adapted to bear upon articles on the table, a series of forwardly facing gravity pawls carried by the last-named bar, the free end of each of said gravity pawls being normally on the table, and means for reciprocating one of the said bars. 95

100 11. In a sheet metal working machine, in combination, a work table having a longitudinal channel, a die block supported over the table and separated therefrom, the die aperture of the block extending through the block, a punch movable downwardly into the die block, a channeled bar slidingly mounted in the channel of the table below the die block, a spring pawl pivotally mounted in the channel of the bar and having an abrupt forward face and an inclined rearward face normally projecting above the surface of the work table, a magnet located below the table in line with the aperture of the die block, a forwardly yielding stop supported over the table in front of the die block and means for reciprocating the bar between each stroke of the punch. 115

120 12. In a sheet metal working machine, in combination, a work table, a punch supported over the table adjacent one end thereof, a series of forming dies arranged along the table beyond the punch, counting mechanism mounted on the table beyond the forming dies, feed mechanism having an 125

- intermittent movement receiving from the punch and delivering to each of the forming dies and to the counting mechanism in succession, a drive shaft and connection between the drive shaft and each of the named operative parts of the machine, that between the drive shaft and the counting mechanism, including a manually-controlled clutch.
13. In a die for folding a channeled sheet metal blank, in combination, a vertically movable pointed anvil block equal in width to the channeled portion of the blank, intermittently operating feed mechanism below the anvil block acting on the blank in a direction transverse to the length of its channel, a tilting support mounted below the feed mechanism and in front of the service position of the anvil block, a die finger slidably mounted on the tilting support, and means for lowering the anvil block, for tilting the support and for advancing the die finger operable in succession in the order named while the intermittently operable feed mechanism is at rest.
14. In combination, a downwardly yielding support for a sheet metal article having a chambered body and a seam at its side which projects below the body, a vertically movable plunger coöperating with the support to form a clamp for the body of the article, the arrangement being such that the projecting edge of the seam abuts against the side of the support when the article is held in the clamp, and a laterally movable hammer located at the side of the support.
15. In combination, a yielding support for a sheet metal article having a chambered body and seams at the sides of the body, a rigid apertured die-block inclosing the said support, the aperture of the die-block being of less width than the body of
- the article and the seams, and a punch having a grooved face adapted to span the chambered body of the article and engage the seams.
16. In combination, a work table, feed mechanism having an intermittent movement for advancing articles on the table and discharging them over the end of the table, a support below the end of the table, a receiver slidably mounted on the support, a plunger horizontally and vertically movable over the table, a counting wheel controlling the vertical position of the plunger, and means for horizontally reciprocating the plunger and for advancing the counting wheel at each movement of the feed mechanism.
17. In combination, a blank cutter, counting mechanism operable upon the blanks, feed mechanism having a series of engaging shoulders extending between the blank cutter and the counting mechanism, a power shaft, and driving connection between the power shaft and each of the first three named parts, that between the power shaft and the counting mechanism including a clutch.
18. In combination, a punch, counting mechanism operable upon parts formed by the punch, feed mechanism having a series of engaging shoulders extending between the punch and the counting mechanism, unitary driving means for all of said parts, and a clutch controlling the operation of the counting mechanism whereby the operation of the counting mechanism may be interrupted without interrupting the operation of the punch and feed mechanism.
